UNITED STATES PATENT OFFICE.

SAMUEL BRAND, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed April 9, 1923. Serial No. 630,956.

This invention relates to cash registers, and more specifically to the mechanism for resetting the totalizers to zero.

The invention is shown applied to machines of the type shown and described in the patents to F. L. Fuller, Nos. 1,242,170 and 1,394,256, issued Oct. 9, 1917 and Oct. 18, 1921, respectively, and in a patent to B. M. Shipley, No. 1,619,796 issued March 1, 1927. 10 The principal object of the present invention is to provide an improved mechanism for resetting the totalizers of a cash register such as that shown in the above mentioned patents, the construction of which 15 is much simpler than that formerly used and the operation more efficient.

A specific object of this invention is to provide novel means actuated by the totalizer wheels to control the differential latch mechanism on resetting operations.

With these and incidental objects in view the invention consists of certain novel features of construction and combination of parts, the essential elements of which are 25 set forth in appended claims and a preferred form of embodiment of which is hereinafter described with reference to the drawings which accompany and form part of this specification.

30 Of said figures:

Fig. 1 is a sectional view taken alongside of an amount bank, and shows the mechanism which breaks the differential latch on resetting operations.

35 Fig. 2 is a detail side elevation of the mechanism for breaking the differential latch on resetting operations.

Fig. 3 is a detail side elevation of a portion of the mechanism for rocking the reset shaft.

40 Fig. 4 is a detail side elevation of the total lever plate and its cooperating mechanism for rocking the reset shaft.

Fig. 5 is a detail view showing part of the mechanism of Fig. 4.

45 Fig. 6 is a detail view showing another part of the mechanism of Fig. 4.

In general.

This invention is designed to greatly simplify the mechanism now used in machines of this type for breaking the differential latch on totalizer resetting operations when its corresponding totalizer element reaches zero. The mechanism included in this machine ren-

ders the operation of the device much more 55 efficient, as there is not only a great reduction in the number of parts, but the time within which the operation may take place has been lengthened.

60 *Keyboard.*

Machines of the type to which this invention is shown applied are provided with a plurality of banks of amount keys which are identical with the bank of keys 20 shown 65 in Fig. 1. As these keys and their cooperating mechanism are fully described and illustrated in the above mentioned patents, only a very brief description thereof will be included herein.

70 The keys 20 of each bank are slidably mounted in a key frame 21 which is supported at its top and bottom by rods 22 mounted in the machine side frames. The keys are depressible and are held in their depressed positions by a detent 23 and a locking plate (not shown). They are released near the end of the operation by means of a shaft 24, arms 25 and rods 26 in a manner well known in the art.

75 There are also one or more banks of control keys which may be used for clerks, transactions, etc.

80 *Differential mechanism.*

85 The differential mechanism of the machine is old in the art. There are a plurality of differential units, one for each bank of keys and one or more differential units to provide for overflow from the amount banks. One 90 of these units is shown in Fig. 1. Each of these units is driven by a pair of cams 27 and 28 fast on a main drive shaft 30 which is given a complete counter-clockwise rotation on each operation of the machine by any suitable means, such as a motor or crank.

95 Cooperating with the cams 27 and 28 are two antifriction rollers 31 and 32, respectively, carried by a Y-shaped lever 33 pivotally mounted on one of the differential unit supporting members 34. These supporting members for all of the differential units are carried by two rods 35 and 36 which in turn 100 are supported by the machine side frames. Pivoted to the upper end of the Y-shaped member is a link 37 which in turn is pivoted to a driving segment 38 pivotally mounted 105 on a bushing 40 carried by the differential

supporting members 34. By these connections when the shaft 30 is given its complete rotation the driving segment 38 will be rocked first counter-clockwise and then clockwise to normal position.

Also pivoted on the bushing 40 are two plates 41 between which are riveted totalizer actuating segments 42. Normally there are three of these segments in machines of this type, as it is desired to actuate three separate lines of totalizers therewith. In the operation of the machine it is necessary to latch the driving segment 38 to the totalizer actuating segments 42. In fact, this is the normal position of the parts. This is accomplished by means of a latch member 43 which is movably mounted on an arm 44 and a bell crank 45 which are in turn pivoted to extensions of the plates 41. The latch member 43 normally engages a shoulder 46 of the driving segment 38 so that when the segment 38 is given its counter-clockwise movement by the means above described, it will carry the totalizer actuating segments 42 with it. It is desired, however, when the totalizer actuating segments 42 have moved a distance corresponding to the value of the key depressed that a separation will be effected between the driving segment and the totalizer actuating segments and the latter locked in their adjusted positions. This is accomplished by the following mechanism. When the totalizer actuating segments are given their counter-clockwise rotation, the end 47 of the bell crank lever 45 will come in contact with the inner end of whichever one of the keys has been depressed. When this occurs the bell crank lever 45 will be rocked clockwise (Fig. 1) and will thereby move the latch 43 out of engagement with the shoulder 46 on the driving segment and at the same time engage the opposite end of said latch with one of a series of notches 48 formed in a plate 50 which is supported by the differential supporting frames 34. This will permit the driving segment 38 to continue its movement to its full extent while the totalizer actuating segments will remain in their set positions. However, when the driving segment 38 is returned to its home position, the upper end thereof will come into contact with a stud 51 carried by the plates 41, which will thereby positively return the totalizer actuating segments to their home positions. As will be later described, the totalizer which is to be actuated is engaged with the totalizer actuating segments 42 during the time that these segments are separated from the driving segment 38. Then when the totalizer actuating segments are returned to home position the amount corresponding to the value of the key depressed will be added on the selected totalizer, as is well known in the art.

Also pivoted to the plates 41 is a beam

52, which is differentially positioned by a roller 49 carried by the Y-shaped member 33, and which at its left hand end is bifurcated to surround a stud 115 carried approximately midway of a link 53. At its upper end this link is pivoted to a segment 54 which is fast to one of a plurality of sleeves 55. The segment 54 has a plurality of teeth cut therein with which an aliner 56 is adapted to cooperate. This aliner is rocked out of engagement from the teeth at the beginning of an operation by means not shown herein so that the differential mechanism may be set, after which the aliner is moved into engagement with said teeth, thereby alining the various parts. At its lower end the link 53 is connected to an arm 57 which, through a spiral segment 58 and a spiral pinion 59 transfers the differential setting to the printing mechanism of the machine, which is neither shown nor described herein.

Totalizers.

The totalizers used in connection with this machine are old and well known in this art, and it is thought that a brief description thereof will be all that is necessary herein. They consist of a plurality of totalizer pinions 60 loosely mounted on tubes 61. The totalizer pinions are arranged in groups, with all pinions of each denominational order located together. In order to select any particular totalizer on a line for operation it is necessary to slide the complete line until the totalizer to be operated is opposite the differential actuating segments. This sliding movement of the totalizer lines is completely described and illustrated in the above mentioned patents and it is not believed to be necessary to include any description thereof herein, as this mechanism forms no part of this invention.

After the selected totalizer has been moved to position to engage with the totalizer actuating segments, the complete line is rocked, so as to bring the selected totalizer pinions into mesh with the totalizer actuating segments.

A portion of the mechanism for engaging the totalizers is shown in Figs. 3, 4 and 5. It is shown, however, because of the relation it bears to other parts of the device which enter into this invention and therefore only a general description thereof will be given. The mechanism for driving the totalizer engaging means consists of a pair of cams 62 and 63, fast on the main drive shaft 30. These cams cooperate with anti-friction rollers 64 and 65 respectively, carried by a Y-shaped member 66 somewhat similar to the member for driving the differential mechanism. Pivoted to the upper end of the member 66 is a member 67 which is provided with a notch 68 which normally engages with a pin 70 carried on a totalizer

engaging spider 71. It can be seen from Figs. 4 and 5 that the spider 71 has three arms 72 which at their ends have hook portions 73. There is one of these arms provided for each of the totalizer lines. When the main drive shaft 30 is given its complete rotation, which, as seen in Fig. 4, is in a clockwise direction, the member 66 will be rocked clockwise about its pivot 74 and will thereby move the member 67 toward the right. As the notch 68 in the member 67 engages with the pin 70 on the spider 71 this spider will be rocked clockwise. Mechanism is provided, but is not shown herein, for connecting the spider 71 with any desired one of the totalizer lines, whereby when the spider 71 is given its rocking movement, as above described, the totalizer line which has been connected therewith will be moved into engagement with the totalizer actuating segments 42 and the desired totalizer will thereby receive its proper actuation.

Totalizing operation.

When it is desired to take a total or subtotal from any particular totalizer, a key in the bank of keys controlling the shifting movement of the totalizer line carrying this particular totalizer will be depressed, as is well known in the art. It is also necessary to move a lever 75 (Figs. 4 and 6) either up or down from its normal adding position to a position corresponding to the totalizer line which carries the totalizer from which it is desired to take a total.

Each of the totalizer pinions is provided with a long tooth 76 in its zero position. The totalizer line which has been selected by the total lever 75 is rocked into engagement with the totalizer actuating segments at the beginning of the operation of the machine. The totalizer actuating segments are then rocked counter-clockwise (Fig. 1) by the driving segment 38 and the totalizer wheels in engagement therewith are rotated backwardly to zero. When the long tooth 76, which is in the zero position of each totalizer wheel, reaches zero from whatever position it had previously occupied it will actuate a mechanism which will break the latch of the differential mechanism, thereby stopping the totalizer actuating segments at this position and permitting the driving segments 38 to continue their movement. The mechanism for breaking the latch under the control of the long teeth of the totalizer pinions will now be described.

Pivoted on two lugs 77 and 78 projecting from the key frame 21 (Figs. 1 and 2) are two levers 80 and 81. The lever 80 at its upper end is pivoted to a segmental plate 82 and at its opposite end has a slot cooperating with a pin 83 carried by the upper end of the lever 81. At its lower end

the lever 81 has a slot which cooperates with a pin 84 carried by the segmental plate 82. The lever 81 normally tends to rock in a counter-clockwise direction (Fig. 1) due to the tension of a spring connected to a stud 79 carried by a projecting portion 85 of said lever, and through the slot and pin connection between them the lever 80 normally receives a clockwise movement. The clockwise movement of the lever 80 is limited however by a pin 79 carried by an extension of the lug 78. Pivoted to a projection 86 of the lever 80 is a short link 87 which carries a pin 112 bearing freely in a similar link 88, which, in turn, is pivoted to one arm 85 of a three-armed spider 90. This spider is pivotally mounted upon the bushing 40 which supports the differentially movable members. Each arm of the spider 90 is provided with a hook-shaped portion 91 having a projecting nose 92 which is normally in such a position as to lie just out of the path of movement of the long teeth 76 of its corresponding totalizer wheels. The arms of the spider 90 are guided by studs 89, carried by one of the plates 34, which studs extend into the hook portions 91. At their ends the studs have flanges which maintain the hook portions in engagement therewith.

The spider 71 which rocks the selected totalizer line into engagement with the totalizer actuating segments is connected by a hub 94 to an arm 95 (Figs. 3 and 5). The arm 95 is fastened to said hub by two screws 96 the heads of which project into short slots 97 in a plate 98 which forms a part of the supporting means for the total lever plate and its cooperating mechanism. It can thus be seen that when the spider 71 is rocked clockwise to engage the selected line, the arm 95 will also be rocked clockwise to the extent of the slots 97.

Pivoted to the plate 98 is a lever 100 (Fig. 6) carrying a roller 101 which is adapted to engage with a slot 102 cut in the total lever plate. At its upper end the lever 100 is bifurcated and surrounds a stud 103 carried by the lower end of a link 104, which at its upper end is pivoted to an arm 105 fast on a shaft 106 supported by the machine side frames. The slot 102 in the total lever plate is so formed that whenever the total lever 75 is moved out of its normal adding position the arm 100 will be rocked counter-clockwise about its pivot, which, due to the engagement of its bifurcated end with the stud 103 will move said stud downwardly into a cut-away portion 107 located at the upper end of the arm 95. It can thus be seen that when the arm 95 is rocked clockwise, due to the movement of the spider 71, to engage the selected totalizer line, the left hand end 108 of the cut-away portion 107 will engage with the stud 103, and

through the link 104 and arm 105 rock the shaft 106 in a counter-clockwise direction (Figs. 4 and 6). Also fast on the shaft 106 is an arm 110 (Figs. 1 and 2) which at its opposite end has a slot cooperating with the pin 112 carried by the short link 87. It can be seen that the two links 87 and 88 form a toggle, and it is evident that when the shaft 106 is rocked clockwise (Figs. 1 and 2), the arm 110 will also be rocked clockwise and will straighten the toggle formed by these two links. Due to the tension of the spring 109 attached to pin 85 the pivotal point of link 87 and lever 86 is maintained in its normal position and the straightening movement of the toggle will move the spider 90 counter-clockwise far enough to bring the noses at the ends of the hooked portions thereof into the path of movement of the long teeth of their corresponding totalizer pinions. Then when the totalizer pinions are rotated backwardly towards zero and the long teeth thereof come in contact with the noses 92 of the hook portions 91 the spider 90 will receive a clockwise movement, and as the toggle formed by the links 87 and 88 has been straightened the lever 80 will be rocked counter-clockwise and the lever 81 clockwise, due to the connection between them and against the tension of the spring. This movement will cause the segmental plate 82 to be moved radially toward the center of the differential mechanism. The bell crank 45 which partly supports the latch member 43 of the differential mechanism has a downwardly extending portion which carries a pin 111 which is so placed as to come into contact with the inner surface of the segmental plate 82 when it is moved inwardly, as just above described. It can, therefore, be seen that when the segmental plate 82 strikes the pin 111 the bell crank 45 will be rocked clockwise, which movement will break the latch of the differentially movable members and cause them to be disconnected from the driving segment 38 at the position corresponding to the position of the totalizer pinion appropriate thereto before the resetting operation commenced.

On totalizing operations, the selected totalizer is rocked out of engagement with the totalizer actuating segments when the pinions have been reset to zero. When, however, it is desired to take a sub-total, mechanism is operated under control of the total lever 75, as is well known in the art, whereby the timing of the parts is changed and the totalizer engaging mechanism is not returned to zero until the amount taken from the totalizer in the first part of the operation has been returned thereto.

Operation.

Items are entered in the usual manner by

well known mechanism, such as shown in the patents referred to.

For total and sub-total taking operations, the total lever 75 is adjusted to control the totalizer engaging means to move a totalizer 70 on one of the lines into engagement with its actuators and to maintain it in engagement for different lengths of time, depending upon the nature of the operation. All of this is accomplished by mechanism 75 shown in said patents operating in the manner set forth therein.

When the total lever 75 is moved out of its adding position into any one of its total or sub-total positions, the arm 100 in Fig. 80 3 is rocked to move the pin 103 into the slot of the arm 95. When the totalizer engaging spider is moved to the right in Fig. 4 to rock a selected totalizer line into engagement with the actuators, the arm 95, which is connected thereto is also rocked to the right, moving the pin 103 to the right. This movement of the pin rocks the shaft 106, which lowers the arm 110 (Fig. 2), thereby rocking the spider 90 to bring the noses 92 90 into the paths of the high teeth of the totalizer wheels. When the selected totalizer is turned by the actuators, the high teeth of the totalizer wheels engage the noses 92, and through the toggle comprising links 95 88 and 87 move the plate 82 radially inwardly into engagement with the pin 111 on the bell crank supporting the latch and disengage the differential actuators from the driving segments 38. The totalizer is 100 now clear and the amounts thereon are being set up on type wheels and indicators through the beam 52 and link 53 in the usual manner. Later in the operation of the machine, the spider 90 is restored to its home position as the totalizer engaging mechanism moves the totalizer out of mesh with the actuators.

While the form of mechanism herein shown and described is admirably adapted to fulfill the objects primarily stated, it is to be understood that it is not intended to confine the invention to the one form of embodiment herein disclosed, for it is susceptible of embodiment in various forms all 115 coming within the scope of the claims which follow.

What is claimed is:

1. In a cash register, the combination of a plurality of lines of totalizers, a plurality of differentially movable members cooperating with all of said lines for resetting said totalizers to zero, and a single member one for each denominational order of the totalizers having integral portions adjacent 125 said totalizer lines for controlling the movement of said differentially movable member on resetting operations.
2. In a cash register, the combination of a plurality of lines of totalizers, differen- 130

tially movable members for adding items thereon and for resetting said totalizers to zero, a single member adapted to be engaged and actuated by a totalizer on any one of 5 said lines on resetting operations, and a plate actuated by said single member to stop said differentially movable members on resetting operations.

3. In a cash register, the combination of 10 a plurality of totalizers differentially movable members for adding items thereon and for resetting said totalizers to zero, a single member one for each order of the totalizers adapted to be engaged and actuated by said 15 totalizers on resetting operations, a radially movable plate one for each denominational order of the totalizer adapted to stop said differentially movable members on resetting operations, a normally inoperative toggle 20 connecting each member with its respective plate, and means for rendering said toggles effective on resetting operations.

4. In a cash register, the combination of 25 a totalizer element, a differentially movable member for adding thereon and for resetting said element to zero, a member adapted to be actuated by said element on resetting operations, a radially movable segment adapted to stop said differentially movable member 30 on resetting operations, a normally inoperative toggle connecting said member and said segment, an arm connected to said toggle, and manipulative means for rendering said toggle effective.

35 5. In a cash register, the combination of a totalizer element provided with a long tooth, a differentially movable actuating segment cooperating with said element, driving means for said segment, and a radially 40 movable segmental plate for disconnecting said actuating segment from said driving

means under control of the long tooth on said totalizer element.

6. In a cash register, the combination of 45 a totalizer element provided with a long tooth, a differentially movable actuating segment cooperating with said element, driving means for said segment, a segmental plate for disconnecting said actuating segment from said driving means under control of the 50 long tooth on said totalizer element, and a plurality of arms for supporting said segmental plate.

7. In a cash register, the combination of 55 a plurality of totalizer elements on three totalizer lines, a plurality of differentially movable segments adapted to engage with said totalizers, means for engaging said totalizer elements with said segments at the beginning of an operation so as to rotate 60 them backwardly to zero, and an actuator control plate having a body portion and a plurality of radially extending arms for controlling the movement of said segment on resetting operations. 65

8. In a machine of the class described, the combination of a plurality of totalizers, differential actuators for adding on and for resetting the totalizers, drivers for said actuators, latches connecting the actuators to 70 the drivers, radially movable members extending opposite the path of movement of said latches, and unitary members cooperating with all of said totalizers during resetting operations for moving said radially 75 movable members into engagement with the latches in various positions to disconnect the actuators from the drivers to control the differential positioning of the actuators by 80 said totalizers.

In testimony whereof I affix my signature.
SAMUEL BRAND.
